UNITED STATES PATENT OFFICE.

ELIX L. SAINO, DOSSEY M. LYNCH, WILLIAM F. DUNBAR, AND JOSEPH H. WEATHERFORD, OF MEMPHIS, TENNESSEE, ASSIGNEES TO SAINO FIRE DOOR AND SHUTTER COMPANY, OF MEMPHIS, TENNESSEE, A CORPORATION OF TENNESSEE.

FIRE DOOR AND SHUTTER.

982,303.

Specification of Letters Patent. Patented Jan. 24, 1911.

Application filed February 11, 1907. Serial No. 356,891.

To all whom it may concern:

Be it known that we, FELIX L. SAINO, DOSSEY M. LYNCH, WILLIAM F. DUNBAR, and JOSEPH H. WEATHERFORD, citizens of the United States, residing at Memphis, Shelby county, State of Tennessee, have invented certain new and useful Improvements in Fire Doors and Shutters, of which the following is a specification.

Our invention relates to certain new and useful improvements in fire doors and shutters, and has especial reference to improvements in those which are made of sheet metal.

The objects of our invention are to so improve the construction of the door or shutter; first;—that it will withstand a severe amount of heat without disintegrating; second; that it will not warp or twist out of shape under severe test; third; that it will transmit a minimum amount of heat; fourth; to improve generally the construction and details. We accomplish these objects as will be more fully set forth hereinbelow in the drawings, specification and claims, in which, however, we have confined ourselves to the construction of the door, and omitted all reference to the shutter.

In the drawings;—Figure 1 is a face view of the door showing it as it appears when closed, and showing the hangers, stay-roller and binders which hold it in place, as they are used ordinarily. Fig. 2 is a partial back elevation and section on the line II—II. Figs. 3 and 7, looking in the direction of the arrow. This and the remaining drawings are on a very much larger scale than that of Fig. 1. Fig. 3 is a sectional elevation on the line III—III of Fig. 2 looking from the right toward the left of Fig. 2. Fig. 4 is a section on the line IV—IV of Figs. 5 and 6 looking down. Fig. 5 is a sectional elevation on the line V—V of Figs. 4 and 6 looking in the direction of the arrows. Fig. 6 is a partial front elevation showing the upper left hand corner of the door shown in Fig. 1. Fig. 7 is a section of the door on the line VII—VII of Fig. 1 looking down. Fig. 8 is a section on the line VIII—VIII of Fig. 1 looking in the direction of the arrow. Fig. 9 is a fragmentary section on the line IX—IX of Fig. 10 looking down. Fig. 10 is a section on the line X—X of Fig. 1 looking in the direction of the arrow.

Referring now to the drawings in which like parts are designated by the same numerals in all views, the door consists fundamentally of a front 1 of sheet metal, an intermediate sheet 2 of refractory substance such as asbestos, and a back 3 of sheet metal. These sheets are supported and stiffened by a metal frame of peculiar construction. The said front is made of one or more widths 1^a, 1^b, 1^c, of sheet metal of commercial sizes, according to the size of the door. These widths, if corrugated, are disposed preferably with their corrugations vertical, as will be more clearly seen by reference to Figs. 6 and 7. The several widths are riveted rigidly together to form the equivalent of a single rigid sheet.

The metal portion 3 of the rear is composed of two or more sections of sheet metal; in the present door, of four sections 3^a, 3^b, 3^c, etc., which, if corrugated, preferably have their corrugations horizontally disposed. As will be seen by reference to Figs. 2 and 3 they are placed with the lower edge of the one overlapping the upper edge of the next, and coupled loosely together by the loose rivets 4, which are put through the vertical slots 5 in the overlap; or we may use some other effective mechanical device which holds these edges in alignment, but which permits the overlap to be diminished by a sliding motion. Thus a vertically expandable rear wall is formed. In Figs. 2 and 3 it will be seen that one or two of the corrugations are flattened to permit easy sliding of the overlap when corrugated sheets are used.

The rear portion of the door on the side away from the fire is composed of the refractory sheet 2 of asbestos or similar material, attached to the inner surface of the metal sections 3^a, 3^b, 3^c, etc., by means of rivets 6 and large washers 7, or by other effective means of riveting the more fragile material to the rear sheet 3 and in contact therewith at intervals throughout its surface.

The front 1 and the rear, composed of sheets 2 and 3, are riveted together by rivets 8 and 9 at the four edges of the door only. As will be seen by reference to Figs. 6, 7, 8 and 10 the rivets 8 at the top and bottom edges are provided with spacing collars or washers 10, which serve to hold the front 1

and the composite rear rigidly apart and allow the free passage of a vertical current of air. The rivets 9 fasten the vertical or side edges of the front and composite back to the metal straps 11, which are portions of the vertical members or stiles of the stiffening frame, but also serve as spacing means to assist rivets 9 in holding front and back rigidly apart to form an air chamber or channel extending throughout the surface of the door. By reference to Figs. 6 and 8 it will be seen that the top of the channel is made to open upward and outward toward the fire side of the door by making the front sheet shorter than the rear at the top. Likewise Fig. 10 shows the rear wall shorter than the front at the bottom of the door, thus allowing the free entrance of air from the rear or cooler side of the door, as shown by the bent arrows. When a high temperature is maintained outside the front sheet, heating said sheet to a red color, the air in this channel or chamber becomes heated by intimate contact therewith, and, since the air in the room to be protected is at a much lower temperature than that on the interior of the door, a "flue-action" or draft will be caused by the continuous displacement of the lighter heated air by the cooler. This fresh supply of cooler air, by absorbing heat from the front sheet during its ascent, allows an increase in the duration and temperature of the exposure to which the door may be subjected without melting the metal.

When corrugated metal, horizontally disposed, is used for sections of the rear metal sheet 3^a, 3^b, 3^c, etc., a series of dead air pockets or channels are formed between the corrugations of said sections and the sheet of refractory material 2, thus reducing to a minimum the radiation of heat through the door. This also provides a transverse stiffness throughout the rear surface of the door.

The stiffening frame is formed of stiles or side framing consisting of channels 12 and bars 11 and 14 (observe Figs. 4, 5 and 7); of top rail, consisting of channel 31 (observe Fig. 8) and of bottom rail, angle 32 (observe Fig. 10). These are riveted or bolted or otherwise rigidly fastened together at their intersecting corners, but each is composed of expansively connected sections or parts that the door as a whole may expand in all directions. In narrow doors it is commercially desirable to omit the sectional formation of the top and bottom rails, since the warping and twisting of relatively short channels and angles is inconsiderable even when subjected to severe difference in temperature between the side edges of the same piece of metal.

Portions of the side framing are protected from severe heat at the side edges of the

door by the overlapping of the side edges of the front metal sheet 1 and the sheet of refractory material interposed, as will be seen by Fig. 7. If the front sheet be corrugated, it is flattened at the side edges for this purpose, and a portion of the flattened marginal edge is bent backward at right angles to form an L in cross section which extends as far back as the rear wall of the stiffening frame. The sheet of refractory material 2 is bent to conform to the inner surface of this L, and the edges of both sheets 1 and 2 are retained by rivets 13, as may be seen by reference to Fig. 4. Between the sheet of refractory material 2 and the remaining portion of the aforesaid flattened marginal edge of the front sheet 1, close in the corner of the L and flatwise to the face of the door, is placed one member of the side framing—the broad flat strap 11, which extends the full length of the door, and is retained by rivets 9. This strap 11, as before mentioned, acts as a spacer bar to hold rigidly apart the front metal sheet 1 and the back composed of refractory sheet 2 and metal sections 3^a, 3^b, 3^c, etc. Being flat against the hot metal sheet at its front and at one edge and against the asbestos sheet in the rear, and having only one narrow edge as a cooling surface, this bar attains almost the same temperature as the front sheet and, therefore, expands and contracts with it without tearing the rivet holes of rivets 9.

The stiffening channels 12 are formed by bending a narrow piece of sheet metal longitudinally to form a square cornered U in cross section with one leg longer than the other. The extra length of this longer leg is then turned outward as indicated by 12^a in Fig. 4. In assembling, these channels are inverted and placed with the portion 12^a between the side edges of the rear metal sections 3^a, 3^b, 3^c, etc., and the asbestos sheet 2, the shorter side coming against the inner surface of the L of the asbestos sheet. These channels 12, being narrower across the U than the width of the flat straps 11, permit the same rivets 9 which pass through the front sheet 1 and bars 11, to pass through the leg 12^a of channel 12, and through the side edges of the rear sections 3^a, 3^b, 3^c, etc., which are superposed. Thus a vertical box-like air passage or flue of considerable dimensions is formed by the channel 12 and asbestos sheet 2, the metal walls of which are shielded from severe heat by the asbestos and the fire-proof wall against which the door is placed in service. Since this stiffening channel is protected and is, therefore, practically cold, there will be a considerable difference between its length and the length of the flat strap 11 to which it is riveted by rivets 9, when the door is subjected to heat on the exposed side. To pre-

vent tearing of the rivet holes and rivets 9 by this unequal expansion, the channel 12 is cut transversely and made of four sections which are long enough to overlap a considerable distance. It will be noted that there are four sections also, 3^a, 3^b, 3^c, etc., in the rear metal sheet 3 of this particular door; and that they are loosely coupled together at bottom and top edges respectively. Thus 10 there are as many overlapping or telescoping sections in channel 12 as there are sections 3^a, 3^b, 3^c, etc., of the rear metal sheet 3.

Special attention is now called to the manner of riveting together these several pieces. The rivets 9 pass completely through the front metal sheet 1, metal strap 11, asbestos sheet 2, portion of channel 12^a and edge of a section of rear metal sheet 3 and binds all of them rigidly together at 15 the points of riveting. But by close inspection of Figs. Nos. 1 and 2 it will be seen that the spacing of rivets 9 is not uniform, but that they are placed in segregated groups, each of which is made up of a few uniformly spaced rivets. Theoretically, these 20 metal sections of rear sheet 3 and channels 12 should be riveted to the front sheet 1 and strap 11 at one part only with a single rivet at the middle of the side edge of each 25 section; but in practice it is found that the extent of riveting employed does not so greatly interfere with the unequal expansion and contraction of the several parts that the warping of the door as a whole, and 30 the tearing of the rivet holes and the rivets, are observed. The number of rivets employed materially increases the strength of the 35 whole structure when distributed as described. Thus it is seen that the vertical expansion of the front sheet 1 and the straps 11 when attaining a red heat is not appreciably restricted by the cooler stiffening channel 12 and by the cooler sections of the rear metal wall 3; and consequently the 40 bulging away from the wall at the middle of the sides of the door will not occur as with rigid stiffening members of one piece, or of several pieces so constructed as to be the expansive equivalent of a single piece.

50 The channels 12 are stiffened and held in alignment by placing a stiff bar of metal 14, which extends the full length of the door, within the channel and retaining it against the back, or the bottom of the U, by the 55 insertion of several bolts 13 through the channel (observe Figs. 4, 5 and 7.) Bolts 13 pass across in front of bar 14 and hold it closely in place but do not prevent the vertical sliding of the several sections of 60 channel 12 along the bar. Bolts 13 are so inserted at the overlap or "telescope" of the joints, and at other points nearby, that they prevent both the bending of the bar and the buckling of the overlapping joints in the 65 channel, but allow the individual expansion

of each section, and their separation from each other. As before mentioned they also pass through the L shaped edges of the front sheet 1 and refractory sheet 2, and fulfil the additional service of retaining them 70 against the stiffening frame and preventing the buckling and twisting of the thin edge as "angle iron" usually does under unequal heating of the edges. The holes for these bolts 13 are slotted longitudinally in the 75 outer metal sheet 1 and refractory sheet 2 and in the overlapping portion of an adjacent channel section. Bar 14 may be bent at its upper end as shown at 15 in Fig. 5 and abut against bar 11 to give the corners 80 rigidity and to allow a fastening such as a wrapping of a portion of upper channel 31, or other means resorted to for securing it at one point in its length.

By referring to Fig. 8 it will be seen that 85 the upper edge of the rear metal section 3^a extends above the front sheet 1 and asbestos sheet 2 and is bent outward toward the front of the door, and then a portion of this edge doubled back, thus forming the 90 deflecting plate or cover 35 projecting over the top of the open channel before mentioned, thereby deflecting outward the air ascending from the interior of the door.

No. 31 is the upper rail or channel, locked 95 or riveted at its upper edge to the outer doubled-back portion 35, and riveted or bolted at its lower edge to the front and back walls of the door by the rivets 8 passing completely through all parts of the door 100 at the top. This channel rail 31 may be made in sections and be reinforced by an alining strip as used with the side channels 12 or not, as the width of the door opening requires. The upper edge of this channel 105 31, being exposed to the heat, may attain a higher temperature than the lower edge, and therefore provision must be made in doors of unusual width for the warping or distortion produced by a great inequality 110 of temperatures of the opposite edges of the same channel. However, the heat is largely deflected away from this exposed surface by the deflected upward current of air before mentioned, and by the proximity of the 115 track 17.

The lower rail or angle 32 of the stiffening frame is shown in Fig. 10. As here shown, it is an angle with vertical leg riveted to the lower edge of sheet 1 and with the other leg extending horizontally backward to the rear face of the door. By reference to Fig. 1 it will be seen that this angle is formed in sections which by overlapping and telescoping freely allow individual expansion and contraction of the several sections. These sections as in the channel 31 may have a trough or channel formed at the rear edge for the reception of a stiffening bar in a manner similar to the stiffening 125 bar in the channel 12. The lower rail 32 is 130

bars 14 in the side channels 12. This part of the frame, the angle 32, has a very small portion exposed directly to the action of the flames as it rests directly upon the sill of 5 brick or concrete 23, and is thereby protected from the heat from below; therefore the sectional formation is employed in wide doors only.

By reference to Figs. 1 and 8 it will be 10 seen that the door is supported in the usual manner by the hangers 16 which are of the usual form, and therefore not specially described. These hangers run on a flat track 17, fastened to the wall 18 by bolts 19 and 15 spacing cones or brackets 20 in the usual manner.

21 is a metal bar fastened to the inner side of the hanger 16, having the arm 22 projecting backward and upward to come 20 under and behind the track 17, so that if the door be hung too close to the sill 23 and expand upward to such extent that the rollers 24 are lifted clear of the track 17, the arm 22 will come upward behind the track 17 25 and press against the same to hold the door to the wall by means of the track.

25 is the ordinary form of stay-roller, and 26 the stay-roll strip which is fastened to the face of the door, and formed with a 30 wedge 26^a as shown in the plan Fig. 9, in order that the door may be jammed closely to the wall when the momentum of the door in closing jams this wedge behind the stay-roller 25.

35 In Fig. 1, the ordinary form of front binders are shown at 27,—27.

28 of Figs. 1 and 7 is a rear binder hoop which consists of a hook-shaped piece of metal, the back of which is countersunk in 40 the wall 18 and fastened to the same by the bolts 29. This binder hook is adapted to engage an opening 30 through the box-shaped side of the stiffening frame and holds the door when shut firmly against the 45 wall.

33 is a spacer bar or washer of metal between the front and back at the point where the hanger bolts 34 pass through the door to prevent drawing of the front and back 50 together at that point (observe Fig. 8).

The door is so hung that under ordinary circumstances the flame will come against the front sheet 1 or face of the door. This sheet when heated expands in a vertical direction rapidly, stretching the joints between the sections of the cooler back and those between the cooler section of channel 12. But, being fastened at the side edges to the ends of the sections 3^a, 3^b, etc., which are 55 cooler and, therefore, expand much less than sheet 1, the front sheet buckles and bulges outward to compensate for the difference in horizontal expansion, tending to become a longitudinal section of a large corrugated 60 cylindrical surface. This bulging, however,

is restricted at the top and bottom of the door by the rails 31 and 32 of the stiffening frame which are riveted by rivets 8 to the bottom of each corrugation, the expansion of sheet 1 being used up by the collapsing "accordion-motion" of the corrugations of the red-hot metal sheet 1. The middle portion, however, not having this restraint does 70 bulge outwardly, the two bulgings, horizontal and vertical, producing a bellying outward or a spherical bulging at the center of sheet 1. By this distortion a larger air space is formed between the front and back, and a suction of air is produced, which air when heated passes out at the top, and sets in 75 motion the cooling current before mentioned. It will be observed that the cool air is drawn from the side of the door away from the fire, entering the door at the bottom, and is discharged as heated air at the top of 80 the door on the fire side only.

The refractory material, or asbestos 2, being held intact by its fastenings to the rear sheet 3, is comparatively undisturbed by changes in temperature of the face of the 90 door, and serves to prevent any considerable amount of heat being radiated through the door.

It will be noted that the rear section 3^a, 3^b, etc., could be fastened horizontally across 95 its middle to the front sheet in a manner similar to that used at the top and bottom of the door, i. e. by use of rivets 8 and spacers 10.

As will be noted the door shown in drawings is formed of sheets of corrugated metal disposed with the corrugations at right angles to each other. It will be readily seen, that the sheets of which the door is composed may be simply flat sheets of metal which, 100 provided they are spaced apart at the top and bottom, and are properly put together to permit the vertical separation of the rear sections, and bulging of the front sheet at the center, will accomplish practically everything that the corrugated sheets do. The corrugated sheets make a stiffer and better door, and for that reason should be preferred in ordinary practice. While we have confined our description to a door, it will be 105 readily seen that by substituting the word "shutter" for "door", this description will apply to a shutter as well.

Having fully described our invention, what we claim and desire to secure by Letters Patent in the United States is:—

1. In a device of the kind described, the combination with a front wall of sheet metal, and a composite back wall of non-combustible materials divided into separate overlapping sections, and means for spacing the walls apart to form an air channel; of means for connecting the sections together whereby a sliding movement of the overlap is allowed transversely to the edges to compen- 115 120 125 130

sate for the unequal expansion of the front and back walls.

2. In a fire door or shutter or the like, consisting of two parallel walls spaced apart to form an air space; the front wall being substantially in a single piece, the back wall being composed of sheet metal and refractory material and being divided into independent overlapping sections with means for rigidly attaching a portion of each section to the front wall but allowing a relative expansile movement between other portions of the section and front wall.

3. A fire door or shutter having a front wall, a back wall of overlapping sections, said sections being composed of sheet metal and sheet refractory material fastened together, means for holding said front and back walls apart to form air space, and means for rigidly fastening said sections to the front wall throughout only a portion of their edges.

4. A fire door or shutter having a front wall, a stiffening frame, a back wall of overlapping sections, said sections being composed of sheet metal and refractory material fastened together, means for holding the front and back walls apart to form an air space, and means for independently fastening each section to the frame whereby a difference between the expansions of the section and frame is allowed.

5. In a fire door or shutter, the combination with a front wall, and a back wall divided into sections whose edges overlap, of means for connecting the overlapping edges of said sections together permitting expansive movement transversely to the adjoining edges of the sections.

6. In a fire door or shutter, the combination with a front wall substantially in one piece, and a back wall of metal composed of a plurality of overlapping sections, of a plurality of loose rivets inserted through slotted holes in the overlapping edges to expansibly connect together and aline the said sections, and means for fastening the said walls together.

7. In a fire door or shutter, the combination with a front wall substantially in one piece, of a back wall of sheet metal comprising a plurality of separate sections, and a plurality of fastenings distributed throughout only a portion of the surface of each section for rigidly securing that portion to the front wall while allowing sliding motions of other portions of the sections with respect to the adjacent portions of the front wall to compensate for a difference in expansion.

8. In a fire door or shutter, the combination with a frame, a front wall attached thereto, and a back wall composed of a plurality of separate sections, of a plurality of fastenings distributed throughout only a portion of the surface of each section for rigidly

securing that portion to the frame while allowing sliding motions of other portions of the section with respect to the adjacent portions of the frame to compensate for a difference in expansion.

9. In a fire door or shutter, the combination with a stiffening frame, a front wall attached thereto, a back wall comprising a plurality of separate sections, and means for spacing said walls apart to form an air space, of a plurality of fastenings distributed throughout only a portion of each section for rigidly securing that portion to the frame while allowing sliding motions of other portions of the section with respect to the adjacent portions of the frame to compensate for a difference in expansion.

10. In a fire door or shutter, the combination with the body portion of sheet metal and refractory material and metallic stiffening members attached thereto, the edges of the refractory material overlapping on the member to protect the said stiffening members from severe heat.

11. In a fire door or shutter, the combination with a main body portion of sheet metal and refractory material, of metallic stiffening members composed of a plurality of sections attached independently thereto, said sections being protected from severe heat by portions of the sheet metal and refractory material.

12. In a fire door or shutter, the combination with a non-combustible main body portion, of metallic stiffening members composed of a plurality of sections attached thereto, means for stiffening into alinement the said sections, means for individually fastening each of said sections to a common member of the main body portion whereby a difference between the expansions of the section and the main body portion is allowed; said stiffening members being insulated from the heat of the common member by an interposed layer of refractory material.

13. In a fire door or shutter the combination with the body part thereof, and stiffening members composed of a plurality of sections of metal attached thereto; of a stiff bar slidably secured in common to the several sections of a member for stiffening into alinement the said sections and for reinforcing the said member.

14. In a fire door or shutter, the combination with front and back walls of non-combustible materials, of metallic stiffening members composed of a plurality of separate sections attached thereto, means for stiffening into alinement the said sections, and means for fastening each of the said sections to a corresponding section of the back wall whereby a difference between the expansions of the section of back wall and section of stiffening member is allowed; said

- stiffening members being insulated from the heat of the front wall by an interposed layer of refractory material.
15. The combination of a fireproof wall having a door opening therein, and a rear binder hook attached to said wall, with a door consisting of metal sheets, a stiffening frame for said door projecting backward from said sheets, the said frame having an opening therein adapted to be engaged by the said hook.
16. A fire door or shutter, having a telescopically expansible stiffening frame built into and forming a component part of the main body portion thereof.
17. In a fire door or shutter, the combination with a main body portion, of a stiffening member divided into sections, and means for stiffening into alinement the several sections of a member.
18. In a non-combustible fire door or shutter, the combination with a main body portion, of stiffening members attached thereto composed of a plurality of sections overlapping at adjoining and freely sliding ends; said sections being alined by their independent fastenings to a common member of the said main body portion and by the overlap of one partially inclosing the complementary form of the other.
19. In a non-combustible fire door or shutter, the combination with a main body portion, of stiffening members attached thereto composed of a plurality of sections lapping at adjoining and freely sliding ends; said sections being alined by their independent fastenings to a common member of the main body portion, and by projecting fastenings of one inserted through slots in the lapping portion of the other.
20. In a non-combustible fire door or shutter, the combination with a main body portion, of stiffening members attached thereto composed of a plurality of sections with adjoining ends free to slide; said sections being alined by their independent fastenings to the said main body portion and by a stiffening bar slidably secured in common to the said sections.
21. In a non-combustible fire door or shutter, the combination with a main body portion, of stiffening members attached thereto composed of a plurality of sections each of hollow substantially U shaped cross section overlapping at adjoining and freely sliding ends; said sections being alined by the overlap of one partially inclosing the complementary form of the other, and by projecting fastenings of one inserted through slots in the overlapping portion of the other.
22. In a non-combustible fire door or shutter, the combination with a main body portion, of stiffening members attached thereto composed of a plurality of sections each of hollow substantially U shaped cross section overlapping at adjoining and freely sliding ends; said sections being alined by the overlap of one partially inclosing the complementary form of the other, and by a stiffening bar slidably secured in common to the said sections.
- of hollow substantially U shaped cross section overlapping at adjoining and freely sliding ends; said sections being alined by the overlap of one partially inclosing the complementary form of the other, and by a stiffening bar slidably secured in common to the said sections. 65
23. In a non-combustible fire door or shutter, the combination with a main body portion, stiffening members composed of a plurality of overlapping sections attached thereto, of a plurality of projecting fastenings of one section inserted through longitudinally slotted holes in the overlapping portion of the other section to connect each section expansibly to the adjoining section. 75
24. In a non-combustible fire door or shutter, the combination with a main body portion, stiffening members composed of a plurality of sections attached thereto, and means for alining and stiffening said sections, of means for fastening each of said sections to a common member of the main body portion whereby a difference between the expansions of the section and the main body portion is allowed. 80
25. In a non-combustible fire door or shutter, the combination with a main body portion, stiffening members composed of a plurality of sections attached thereto, and means for alining and stiffening said sections, of a plurality of fastenings distributed throughout only a portion of the edge of each section for rigidly securing that portion to the main body portion while allowing sliding motions of other portions of the section with respect to the adjacent portions of the main body portion to compensate for a difference in expansion. 90
26. In a fire door or shutter, the combination with front and back walls of non-combustible materials, of metallic stiffening members composed of a plurality of sections attached thereto, and means for alining and stiffening said sections, of means for fastening each section to a corresponding section of the back wall whereby a difference between the expansions of the section of back wall and the section of stiffening member is allowed. 105
27. In a fire door or shutter, the combination with front and back walls, stiffening members composed of a plurality of sections attached thereto, and means for alining and stiffening said sections; of a plurality of fastenings distributed throughout only a portion of the edge of each section for rigidly securing that portion to a corresponding portion of a section of the back wall while allowing sliding motions of other portions of the section of stiffening member with respect to the adjacent portions of the section of back wall to compensate for a difference in expansions. 115
- 100
- 110
- 120
- 125

28. In a non-combustible fire door or shutter, the combination with a main body portion, stiffening members composed of a plurality of hollow sections in alinement attached thereto, of a plurality of fastenings to confine a stiffening metal bar within the several hollow sections in common, which are thereby slidably secured to the said metal bar and stiffened into alinement.

10 In testimony whereof we have signed our

names to this specification, in the presence of two subscribing witnesses.

FELIX L. SAINO.

DOSSEY M. LYNCH.

WILLIAM F. DUNBAR.

JOSEPH H. WEATHERFORD.

Witnesses:

F. M. FLANERY,

H. H. HIGBEE.
